BRIDGING PLUG.

Application filed August 24, 1927. Serial No. 215,100.

This invention relates to improvements in bridging plugs for plugging up a casing in a well.

An object of the invention is to provide 6 an improved bridging plug which can be seated so as to seal off the casing or to plug it up at any location within the well either intermediate the ends of the casing or at the very bottom.

10 Another object of the invention is to provide an improved bridging plug which, when seated within the casing, will be held against upward movement or downward movement for purposes hereinafter to be set forth.

Another object of the invention is to provide 20 a bridging plug which is formed of a readily destructible material so that after the plug has been seated, it will be relatively easy to remove the same for further drilling operations by a drilling tool.

Another object of the invention is to provide 25 a bridging plug which has passages therethrough, so that as the bridging plug is lowered into a well, fluid in the well may pass upwardly through the plug, and when the plug is seated, these passages will be closed to prevent any flow of fluid therethrough.

30 A further object of the invention is to provide an improved bridging plug carrying a sealing device which will engage the interior of the well casing and effectively form a packer or seal between the body of the plug and the casing to prevent leakage.

It will be understood that the improved 35 bridging plug is designed to form a bridge or plug across the casing which may be used for many different purposes, such as cementing operations.

With the foregoing and other objects in view, which will be made manifest in the following detailed description and specifically pointed out in the appended claims, 45 reference is had to the accompanying drawings for an illustrative embodiment of the invention, wherein:

Figure 1 is a vertical section through a well casing and through the improved 50 bridging plug shown therein in the position wherein the plug is being lowered into the well.

Figure 2 is a view similar to Figure 1, showing the bridging plug after it has been 55 seated.

Figure 3 is a view in side elevation of the improved bridging plug.

Figure 4 is a plan view taken in the direction of the arrow 4 upon Figure 3.

Figure 5 is a horizontal section taken 60 upon the line 5-5 upon Figure 3.

Figure 6 is a horizontal section taken upon the line 6-6 upon Figure 3.

Figure 7 is a partial view in vertical section, taken upon the line 7-7 upon Figure 4 to illustrate a detail of construction.

Referring to the accompanying drawings wherein similar reference characters designate similar parts throughout, the improved bridging plug consists of a plurality 70 of segments 10 forming a cylinder. The number of segments illustrated upon the drawing is four, such number being taken to facilitate the illustration of the device, but it will be readily understood that the 75 improved bridging plug can use any desired number of segments which will co-operate to form a complete cylinder of a diameter slightly smaller than the interior diameter of the casing C within which the plug is to 80 be used. These segments 10 are held together at their upper ends by means of a circular disc of flexible material 11 which may be rubber or leather. Elongated slots 12 are formed in the disc 11, and screws 13 having 85 relatively large heads, extend through the slots 12 forming a pin and slot connection between the upper ends of the segments 10 and the disc 11 so that the segments can separate to expand the cylinder. The interior 90 surfaces of the segments 10 are so formed that they will co-operate to form a conical bore through the plug, complementary to a tapered mandrel 14. The segments 10 and the mandrel 14 are preferably formed of 95 wood so that the plug can easily be drilled out of the casing by a drilling tool for further drilling operations. A draw bar 15 has its threaded lower end screwed into the upper end of the mandrel 14 so that by pulling 100 upwardly on the draw bar 15 so as to raise the mandrel 14 within the segments 10, the segments will be moved into expanded position and caused to engage the interior surface of the casing C. On the exterior of 105 each of the segments 10 and adjacent their respective upper ends, there is formed a groove 16 which is dovetailed in cross section as clearly shown upon Figure 5, and which has its back or bottom upwardly and 110

inwardly inclined slightly. Slidable slips 17 are slidable in these grooves and are retained in the grooves by the disc 11. These slips have upwardly directed teeth 18, which, 5 when they engage the casing C, will prevent upward movement of the plug within the casing. Each of the segments 10 has a stationary slip 19 secured to its lower end, these slips being provided with downwardly directed teeth 20 which, when they engage the casing, will prevent downward movement of the plug. Horizontal grooves 21 are formed upon the exterior surfaces of the segments 10, and these receive rubber packing rings 10 22. On the interior surface of each of the segments 10 there is formed a groove 23. The grooves 23 extend upwardly from the bottom of each segment to a point some distance below the top of each segment. They 15 are so arranged that when the mandrel 14 is in its bottom position as shown in Figure 1, the grooves terminate above the top of the mandrel, but when the mandrel is in its uppermost position as shown in Figure 2, 20 the grooves 23 terminate below the top of the mandrel so that they are effectively closed by the mandrel when in this position. The draw bar 15 extends upwardly through an aperture 24 formed in the disc 11 and 25 has an eye 25 formed on its upper end providing for the attachment of the sand line S. The draw bar has a ring 26 secured thereto by means of radial arms 27, thus forming a spider adapted to rest on top of the disc 11 when the plug is lowered into the well.

The operation of the improved bridging plug is as follows: If it is desired to plug off the casing at a predetermined level such 40 as 2500 ft. from the surface, the plug is caused to assume the position shown in Figure 1 and attached to the sand line S. As it is lowered into the fluid filling the casing, the segments 10 being formed of wood, tend 45 to float. They are caused to sink within the fluid by the ring 26 bearing evenly upon their upper ends. As the plug is being lowered, the slidable slips 17 tend to slide downwardly and outwardly within their respective grooves and engage the interior of the casing. When the desired level has been reached, an upward pull is imparted to the sand line S. The slidable slips 17 wedge between the backs of their respective grooves 50 and the casing, and prevent the upward movement of the segments 10. The pull on the draw bar 15 raises the mandrel 14 causing it to expand the segments and to seal off the grooves 23. It will be understood 55 that these grooves, when the plug was being lowered into the well, permit the circulation fluid to flow up through the plug and through the space between the arms 27. When the plug is expanded as a result of the 60 separation of the segments by the mandrel

14, the stationary slips 20 are also caused to engage the casing and prevent downward movement of the plug. The rubber rings 22 also engage the casing and are compressed, thus forming a packer or seal to prevent the leakage of fluid between the exterior surface of the segments 10 and the casing. The improved bridging plug preferably employs both upwardly directed slips and slips having downwardly directed teeth. 70 The teeth 18 prevent the plug from being forced upwardly in the event that the well should start to "heave." The downwardly directed teeth 20 prevent the plug from being forced downwardly by any pressure within the casing on top of the plug. As the mandrel 14 is formed of wood, the sand line S can be pulled upwardly with a sufficient force to draw the draw bar 15 out of the mandrel. It is drawn loose by merely stripping off the threads formed in the mandrel by screwing the lower end of the draw bar 15 into it. This leaves the bridging plug in the casing and sealing the casing at the proper level as shown in Figure 2. 80 The slips 17 and 19 are preferably formed of cast iron or an equivalent frangible material which can be easily broken up by a drilling tool whenever it is desired to drill out the plug for further drilling operations. 90

The above described operation is in connection with plugging up the casing at some distance above its bottom. If it is desired to plug up the casing at the very bottom of the well, the draw bar 15 is left detached from the mandrel. The mandrel is held in its lowered position by merely driving a nail through one of the segments and into the mandrel. The plug is then placed in the casing and is forced downwardly by any heavy article such as a bailer attached to the sand line S. The mandrel 14, having its lower end projecting below the segments 10, encounters the bottom of the well. By striking the top of the segments 10 with the bailer, the segments will be caused to slide downwardly upon the mandrel and to be expanded thereby into engagement with the casing, shearing off or bending the nail which temporarily held the mandrel in the 105 position shown in Figure 1, relatively to the segments. 110

From the above described construction, it will be appreciated that a novel bridging plug is provided which can be easily, quickly and cheaply constructed, and which will effectively seal off or plug up a well casing. Furthermore, it is an easy matter to drill out the improved plug to carry on further drilling operations. The plug is held stationary in the casing against movement in either upward or downward directions, and carries a sealing means which will prevent leakage either between the segments 10 and the casing C, or between the sides of adjacent 120 125 130

segments which are separated slightly when the segments are expanded.

It will be understood that various changes in the details of construction may be made 5 without departing from the spirit or scope of the invention as defined by the appended claims.

We claim:

1. A bridging plug comprising means 10 forming a plurality of segments of a cylinder, a mandrel capable of being moved upwardly within the segments to separate them, means attached to the mandrel for lowering the device within a well casing, 15 said means being detachable after the segments have been expanded, so as to be capable of being removed from the well casing, leaving the plug therein, and slips carried by said segments engageable upon the casing, some of the slips being designed to 20 prevent upward movement of the plug within the casing, and others being designed to prevent downward movement of the plug within the casing.

2. A bridging plug comprising a plurality 25 of segments of a cylinder, means for separating said segments into engagement with a well casing, and elastic means surrounding said segments adapted to be caused to engage the casing when the segments are separated to form a tight seal therewith, said segments having slips thereon, said slips being designed to engage the well casing so as to prevent upward and downward 35 movement of the plug relatively thereto.

3. A bridging plug comprising a plurality 40 of segments of a cylinder, means for expanding said plug into engagement with a well casing, and elastic means surrounding said segments adapted to be caused to engage the casing when the plug is expanded to form a tight seal therewith, said segments having grooves therein, slips slideable in the 45 grooves and adapted to engage the interior of the well casing to prevent upward movement of the plug therein, and stationary slips carried by said segments engageable upon the interior of the well casing adapted to prevent downward movement of the plug 50 therein.

4. A bridging plug comprising a plurality 55 of segments of a cylinder, there being passages formed upon the segments permitting fluid to flow therethrough when the plug is lowered within a well casing, means for separating said segments to expand the plug into engagement with the well casing, said means serving to close said passages when the plug is expanded.

60 5. A bridging plug comprising a plurality

of segments of a cylinder, a tapered mandrel adapted to be caused to slide upwardly within the segments to separate them, there being grooves formed upon the segments, slips slideable in the grooves and engageable upon the interior of a well casing to prevent upward and downward movement of the plug therein, and stationary slips carried by said segments engageable upon the well casing to prevent the downward movement of the plug therein, there being passages formed upon the segments adapted to allow fluid to flow therethrough when the plug is being lowered, said passages being so arranged as to be closed by the mandrel when the drill 65 is moved into its uppermost position to expand the segments.

6. A bridging plug comprising a plurality 70 of segments of a cylinder, a tapered mandrel adapted to be caused to slide upwardly within the segments to expand them, there being grooves formed upon the segments, slips slideable in the grooves and engageable upon the interior of a well casing to prevent upward movement of the plug therein, and elastic bands surrounding said segments adapted to be caused to engage the well casing to form a tight seal therewith.

7. A bridging plug comprising a plurality 75 of segments of a cylinder, a tapered mandrel adapted to be caused to slide upwardly within the segments to separate them, there being grooves formed upon the segments, slips slideable in the grooves and engageable upon the interior of a well casing to prevent upward movement of the plug therein, and stationary slips carried by said segments engageable upon the well casing to prevent the downward movement of the plug therein, there being passages formed upon the segments adapted to allow fluid to flow therethrough when the plug is being lowered, said passages being so arranged as to be closed by the mandrel when the drill 80 is moved into its uppermost position to expand the segments, a flexible member positioned over the top of said segments, headed pins extending through slots in said flexible member to join the segments together but to permit them to be separated, and a draw bar extending through the flexible member and threaded into the mandrel so as to be capable of being pulled out of the mandrel, said draw bar carrying an apertured flange 85 engageable upon the top of the flexible member.

In testimony whereof we have signed our names to this specification.

E. M. REARDON.
